WINDOW LOCK

John Keane, New York, N. Y.

Application October 2, 1944, Serial No. 556,692

1 Claim. (Cl. 292—145)

1

This invention relates to window locks, and aims to provide a positive and safe window lock to prevent sliding of the sashes and thereby prevent unauthorized opening of the window.

Another object of the invention is the provision of a window lock which may be readily attached by an unskilled person, and which is simple in construction and operation as well as inexpensive in cost of manufacture.

The above and other objects will become apparent in the following description, wherein characters of reference refer to like-numbered parts in the accompanying drawings. It is to be noted that the drawings are intended for the purpose of illustration only, and that it is neither desired nor intended to limit the invention necessarily to the specific details of construction shown excepting insofar as they may be deemed essential to the invention.

Referring briefly to the drawings:

Fig. 1 is a fragmentary perspective view, partly in section, of the upper and lower sashes of a window, showing the lock applied to the former.

Fig. 2 is another fragmentary view of the window sashes, showing the lock in side elevation.

Fig. 3 is a cross-sectional view taken on the line 3—3 of Fig. 2.

Fig. 4 is a cross-sectional view taken on the line 4—4 of Fig. 2.

Fig. 5 is a view similar to Fig. 2, showing the bolt in unlocked position.

Fig. 6 is a cross-sectional view taken on the line 6—6 of Fig. 2.

Referring in detail to the drawings, the numerals 10 and 11 show respectively the upper and lower window sashes, and one of the side frame members of the upper sash is indicated at 12. It is preferably to the member 12 that the lock is attached.

The lock comprises a frame which is substantially L-shaped in plan view and consists of a single plate or the like bent to form the two arms 13 and 14 at right angles to each other. Since the side sash members such as 12 are usually beveled or gouged out substantially as shown, it is advisable that the material of the lock frame be non-resilient so as to maintain a right angle between the arms thereof in spite of the gouged out moulding of the said sash member.

The arm 14 has, prior to shaping of the device, an upward extension which is bent down against the arm 14 and shaped as shown to form a central horizontal sleeve-like housing 15 substantially rectangular in cross-section and with the upper and lower strips 16 and 17 flush against

2

the arm 14. The lower strip 17 is then riveted or otherwise secured against the arm 14.

A small vertical strip 18 of the sash member 12 and a relatively wider strip 19 at right angles thereto, provide suitable surfaces for attaching the lock frame to the sash, and therefore holes are provided in the free ends of the arms 13 and 14 for the reception of screws to attach the lock stably to the sash.

10 A slide bolt 20 is snugly yet slidably mounted in the sleeve 15 and is provided with a bent extremity 21 which serves as a handle or grip whereby the bolt may be pulled outward or pushed inward into the sleeve. A set screw 22 passes through the outer wall of the housing or sleeve 15 and is adapted to lock the bolt 20 at any position therein. Instead, however, the bolt might be provided with a longitudinal slot and a fixed pin provided instead of the set screw to 15 register in the bolt slot, thereby setting the inward and outward limit stops of the bolt, not shown.

In Figs. 1 and 2 the bolt 20 is shown withdrawn partway from its sleeve 15 and overlapping the lower sash 11. Hence, as is apparent, the bolt provides an obstruction to the lower sash which prevents either sash from being moved. In its other extreme position, shown in Figs. 4 and 5, the bolt handle 21 is clear of the lower sash and thus permits free sliding of either sash. When the bolt is in extended or locking position, the set screw 22 is tightened against the bolt to prevent movement thereof.

It is apparent that when the device is in locking position it would be impossible for an unauthorized person to slide the bolt inward with a tool to unlock the window. Such a safety factor is not present in the common type of pivoted window lock, as is well known.

35 40 Obviously, modifications in form and structure may be made without departing from the spirit and scope of the invention.

I claim:

An attachment for an upright sash member 45 substantially rectangular in cross-section, comprising a relatively wide base L-shaped in plan view thereby providing a pair of arms at right angles to each other, means for securing said base to said member with one surface of one of said arms flush against one surface of said member and the other of said arms flush against the adjacent surface of said member, said one of said arms having a doubled-back extension from the free end thereof, said doubled back extension having the horizontal edges thereof secured

against the horizontal edges of said one of said arms and having the horizontal mid-portion thereof raised from and parallel with said one of said arms thereby providing a longitudinal passage between said raised mid-portion and said one of said arms, said doubled-back extension between said raised mid-portion and said first-named horizontal edges providing upper and lower horizontal walls closing said passage at the top and bottom respectively thereby providing a 10 rectangular cross-section to said passage, a bolt rectangular in cross-section slidably mounted in said passage and having one end thereof protruding from the passage through one end thereof, said protruding end of said bolt having a right- 15

angle extension thereon to provide a finger grip.
JOHN KEANE.
